United States Patent Office

Des. 228,954
Patented Oct. 30, 1973

228,954

PAIR OF SPECTACLES

Anthony Shindler, Brookline, Mass., assignor to American Optical Corporation, Southbridge, Mass.

Filed Mar. 22, 1972, Ser. No. 237,228

Term of patent 14 years

Int. Cl. D16—06

U.S. Cl. D57—1 F

FIG. 1

FIG. 2

FIG. 3

FIG. 1 is a front elevational view of a pair of spectacles embodying my new design;

FIG. 2 is a top plan view thereof, the temples being broken away for convenience of illustration; and

FIG. 3 is an elevational view of one side of the pair of spectacles, the opposite side thereof being of substantially the same appearance.

I claim:

The ornamental design for a pair of spectacles, as shown and described.
